(57) **CLAIM**

The ornamental design for a display screen with graphical user interface for a mobile electronic device, as shown and described.

DESCRIPTION

FIG. 1 is a front view of a mobile electronic device with transitional graphical user interface showing the first image of a sequence; and,

FIG. 2 is the second image thereof.

The appearance of the transitional image sequentially transitions between the images shown in FIGS. 1 and 2. The process or period in which one image transitions to another forms no part of the claimed design.

The broken line showing of a mobile electronic device and the display screen illustrate environmental structure and the article of manufacture, respectively. None of the broken lines form part of the claimed design.
